United States Patent Office

Des. 213,191
Patented Jan. 14, 1969

213,191

CHAIR

George A. Koch, Cobourg, Ontario, Canada, assignor to Curtis Products Limited, Cobourg, Ontario, Canada

Filed Nov. 13, 1967, Ser. No. 9,373

Term of patent 14 years

U.S. Cl. D15—1
Int. Cl. D6—01

The drawing is a perspective view of a chair showing my design. The back of the chair is conventional in appearance. The dominant features of my design reside in those portions shown in full lines on the drawing.

I claim:

The ornamental design for a chair, as shown and described.
